(57) **CLAIM**

The ornamental design for a teether, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a first embodiment of a teether, showing my new design;

FIG. 2 is a rear elevational view thereof;

FIG. 3 is a perspective view thereof;

FIG. 4 is a bottom plan view thereof;

FIG. 5 is a right side elevational view thereof;

FIG. 6 is a front elevational view thereof;

FIG. 7 is a left side elevational view thereof;

FIG. 8 is a top plan view of the second embodiment of a teether;

FIG. 9 is a rear elevational view thereof;

FIG. 10 is a perspective view thereof;

FIG. 11 is a bottom plan view thereof;

FIG. 12 is a right side elevational view thereof;

FIG. 13 is a front elevational view thereof;

FIG. 14 is a left side elevational view thereof;

FIG. 15 is a top plan view of the third embodiment of a teether;

FIG. 16 is a rear elevational view thereof;

FIG. 17 is a perspective view thereof;

FIG. 18 is a bottom plan view thereof;

FIG. 19 is a right side elevational view thereof;

FIG. 20 is a front elevational view thereof; and,

FIG. 21 is a left side elevational view thereof.
